[57] CLAIM

The ornamental design for a water purification ionic gas generator, substantially as shown and described.

DESCRIPTION

FIG. 1 is a front perspective view of a water purification ionic gas generator, showing our new design;
FIG. 2 is a front elevational view thereof;
FIG. 3 is a left side elevational view thereof, the right side being a mirror image of the left side shown;
FIG. 4 is a rear elevational view thereof;
FIG. 5 is a top plan view thereof; and
FIG. 6 is a bottom plan view thereof.

FIG. 1.FIG. 5.FIG. 6.FIG. 2.FIG. 3.FIG. 4.
